UNITED STATES PATENT OFFICE

2,442,512

REVERSIBLE FLOW CENTRIFUGAL PUMP

Clarence William Rubison, Fort Lauderdale, Fla.

Application February 27, 1946, Serial No. 650,473

1 Claim. (Cl. 103—3)

1 This invention relates to centrifugal pumps, and has more particular reference to an improved pump of this kind in which the flow of liquid through the pump casing may be readily reversed without the use of valves or changing the direction of rotation of the impeller.

More specifically, the invention contemplates a centrifugal pump embodying a stationary casing having two impeller chambers arranged in adjoining side-by-side relation and communicating with each other through the adjoining sides thereof, and a single rotary vane impeller mounted within the casing and having liquid inlets at opposite sides thereof inwardly of the vanes, said impeller being movable to a position within either desired impeller chamber so as to determine the direction of flow of the liquid.

A further object of the invention is to provide a pump of the above character embodying simple and efficient means for priming the same by introduction of priming liquid through the impeller shaft and the hub of the impeller.

The exact nature of the present invention, as well as more specific objects and features thereof, will become apparent from the following description when considered in connection with the accompanying drawings, in which:

Figure 1 is a view partly in elevation and partly in central transverse section of a centrifugal pump constructed in accordance with the present invention.

Figure 2 is a view of the pump shown in Figure 1, partly in side elevation and partly in section along the line 2—2 of Figure 1.

Referring in detail to the drawings, the present centrifugal pump comprises a stationary casing 5 having two impeller chambers 6 and 6a arranged in adjoining side-by-side relation and communicating with each other through relatively large openings provided in the adjoining sides thereof as at 7. The casing 5 has a peripheral opening or passage 8 for the intake or discharge of liquid to or from each chamber 6 and 6a.

A drive shaft 9 is axially journaled in and longitudinally slideable relative to the casing 5, and a single rotary vane impeller 10 is secured in the drive shaft 9 within the casing. The impeller 10 has liquid inlets 11 at opposite sides thereof inwardly of its transverse vanes 12, and the impeller is movable to a position within either impeller chamber so as to determine the direction of flow of liquid through the pump. In the embodiment shown, the impeller is shifted

2 to the desired chamber by sliding the drive shaft 9 longitudinally.

As shown, the passage 8 of chamber 6 is connected with a conduit 13, and the passage 8 of chamber 6a is connected with a conduit 13a. By positioning the impeller 10 within the chamber 6, the liquid may be drawn through the conduit 13a into chamber 6a so as to enter the impeller through the liquid inlets 11 at the right side of said impeller as viewed in Figure 1, the liquid being discharged outwardly by the vanes 12 through the outlet 8 connected with the conduit 13. In order to reverse the flow of the liquid, it is simply necessary to shift the impeller 10 from the chamber 6 to the chamber 6a, whereupon the liquid will be drawn through conduit 13 into chamber 6 and will then be delivered by the impeller from chamber 6a through conduit 13a. This is accomplished without the use of any special conduit and valve arrangement and without changing the direction of rotation of the impeller.

As shown, the casing 5 is constructed of two similar sections 14 and 14a which are bolted together in side-by-side relation as at 15 and which are provided at their outer sides with removable closure plates 16 and 16a having central bearings 17 and 17a in which the drive shaft 9 is journaled and longitudinally slideable. The bearing 17 is preferably constructed with a stuffing box to prevent leakage of fluid outwardly therethrough, which stuffing box includes the adjustable gland 18.

Means is provided to readily and effectively prime the pump by supplying liquid to the pump casing through the shaft 9 and the hub of impeller 10. For this purpose, an end portion of the shaft 9 has an axial bore 19 which opens through the free end of the shaft carried by the bearing 17a and which communicates at its other end with a radial passage 20 provided through the hub of impeller 10. Secured on the bearing 17a is a hollow cap 21 provided with a fluid supply pipe 22. Thus, when fluid is introduced through pipe 22, cap 21, bore 19, and passage 20 into the casing 5, the pump may be readily primed. Cap 21 has a bore coaxial with that of bearing 17a and of such size as to accommodate the adjacent end of shaft 9 when the impeller 10 is shifted to a position within the chamber 6a.

From the foregoing description, it is believed that the construction, operation and advantages of the present invention will be readily understood and appreciated by those skilled in the

art. The casing 3 may be suitably mounted so as to remain stationary, such as by providing the plates 16 and 16a with supporting brackets 23 adapted to be bolted or otherwise secured upon fixed supports 24 disposed at opposite sides of the pump casing. Minor changes may be made in details of construction, such as fall within the spirit and scope of the invention as claimed.

What I claim is:

In a reversible flow centrifugal pump, a stationary casing having two impeller chambers arranged in adjoining side-by-side relation and communicating with each other through the adjoining sides thereof, said casing having a peripheral passage for the intake or discharge of liquid to or from each chamber, a drive shaft journaled in the casing, and a single rotary vaned impeller secured on said drive shaft within the casing, said impeller having liquid inlets at opposite sides thereof inwardly of its vanes and being movable to a position within either desired impeller chamber for reversing the flow of liquid through the pump without changing the direction of rotation of the impeller, said casing being provided with axial bearings in 25

which the drive shaft is journaled, said impeller including a hub having a radial passage, an end portion of said drive shaft having an axial bore communicating with said passage in the impeller hub, a cap secured to one of said bearings, the bore of the drive shaft opening through an end of the latter into said cap, and a fluid supply pipe communicating with said cap for the introduction of priming fluid into the pump casing.

10 CLARENCE WILLIAM RUBISON.
